TYPE-WRITING MACHINE.

1,053,926.

Specification of Letters Patent. Patented Feb. 18, 1913.

Original application filed April 25, 1910, Serial No. 557,330. Divided and this application filed April 4, 1912. Serial No. 688,358.

To all whom it may concern:

Be it known that I, WILLIAM J. NEIDIG, a citizen of the United States, residing at Madison, in the county of Dane, State of Wisconsin, have invented a certain new and useful Improvement in Type-Writing Machines, of which the following is a specification, reference being had thereto to the accompanying drawings.

10 My present invention is a division of that of my application filed April 25, 1910, Serial No. 557,330, and also is included within the generic invention which is described and claimed in my co-pending application filed

15 April 20, 1908, Serial No. 428,212.

The leading objects of my invention, as common to the generic invention of the said applications and to the present branch or division thereof, are first, to indicate during 20 several progresses of the sheet the distance remaining from the current printing point to the bottom edge of the sheet, or to a point a definite distance therefrom, and this automatically, irrespective of the length of the 25 sheet, so that the operator may know considerably in advance of the time to remove the sheet how much space remains to him; and second, to supply him with further indicating means whereby he may know of the 30 arrival of the bottom edge of the sheet at a predetermined distance from the printing point.

In the present division of the invention I employ an operative member, indicating 35 means controlled by the said member, slip-drive connections for imparting to said operative member movement correlated or coordinated with that of the sheet-advancing means, and sheet-controlled means for detaining 40 said member in the presence of the sheet and releasing it on the passage of the bottom of the sheet to move simultaneously with the sheet-advancing means and thereby bring about the actuation of the indicating means.

Various forms and kinds of indicating means suitable to be employed for indicating the arrival of the bottom of a sheet at a given distance from the printing point are 50 known in the art in various connections, and are suitable to be employed in carrying the broader phases of the invention into effect. Preferably, however, I employ a scale or series of indices and a pointer or index, one

thereof fixed and the other movable in unison with the sheet-advancing means, so that the relative shift in position as the operative member moves indicates the approach of the bottom of the sheet closer and closer to the predetermined point, which usually is the printing point. Preferably, also, I employ an operative member which is rotary, so that it may turn or rotate coördinately with the advance of the sheet after the operative member has been called into movement, and for convenience I apply the scale or series of indices to the said rotary operative member and mount the pointer or index upon some part of the carriage. The sheet-advancing means ordinarily employed in type-writing machines is a platen, and accordingly I have herein combined the rotary operative member with the platen through the slip-drive connections, although the invention is not limited in all cases to the combination of the said member with the ordinary platen. The slip-drive connections may be of any approved type, but preferably are of a character operating chiefly or wholly by friction. The sheet-controlled means for detaining the rotary operative member in the presence of the sheet and releasing it on the passage of the bottom of the sheet includes a feeler adapted to feel for and engage with the sheet, and means in connection therewith for holding or detaining the rotary operative member from movement to actuate the indicating devices so long as the sheet controls the position of the feeler, the said parts operating to release the said member to rotate in unison with the sheet-advancing means when the passage of the bottom of the sheet releases the feeler.

The present division of the invention consists in improvements in the construction of the operative member and in the slip-drive connections of the said member, as well as in the means and manner of combining the said member and slip-drive connections with each other.

An embodiment of the invention is illustrated in the accompanying drawings, in which—

Figure 1 is an end view of a portion of a typewriting machine carriage showing the said embodiment applied thereto; Fig. 2 is a view in vertical section on the line A. A., Fig. 1, of a portion of the same, but

with the spring 7 somewhat shifted so as to appear more clearly in the drawings; Fig. 3 is a top or plan view of the parts shown in Fig. 1; and Fig. 4 is a sectional view of a 5 modification.

Having reference to the drawings:—the usual platen-arbor 13, bearing thereon the usual platen 10 for advancing the sheet, is journaled in the ends of the usual carriage-frame 12, the said carriage-frame being movable laterally in the usual manner upon the main frame, and the said platen being rotated in usual manner by line-spacing mechanism not shown herein, as will be understood by those skilled in the art.

The central member of the present embodiment of my invention, namely the operative member, may be called from one of its functions an index-carrier or an indicator. 20 The indicator or index-carrier which I prefer to employ is constructed in the form of an annular shell 6 having a peripheral face provided with a series of indices which cooperate with the fixed pointer or index 34 25 attached to the carriage frame 12, as will be explained.

In typewriting machines as ordinarily constructed, the line-space mechanism for advancing the sheet operates to start the 30 platen into action with considerable suddenness, the platen thereupon moving for a short distance with considerable velocity, and at the end of the movement coming to rest with considerable abruptness. In the 35 case of a part connected frictionally with such an abruptly moving platen, the friction must be sufficient to overcome in starting it the inertia of the part, and sufficient to overcome in stopping it the momentum of the 40 part, otherwise the part will not remain in the same angular relation with the platen, but will shift in one direction when started and in the other when stopped. In practice it is found that such a part tends to 45 drift in line-space direction; that is to say, the momentum of the part shifts it forwardly more than the inertia of it shifts it backwardly, the stopping action being more sudden than the starting. The greater 50 the momentum of such a part, the greater will be its tendency to shift. It is possible to overcome the tendency by increasing the friction, but in a paper-controlled mechanism of the delicacy of this one, it is desirable 55 that the friction be as light and smooth as possible, in order that the work of the sheet in controlling the same may not be beyond the ability of a fragile substance like thin paper to perform. I have therefore 60 found it desirable to reduce to the lowest convenient point the inertia of the carrier I employ by using a light annular shell for a carrier, as illustrated in Fig. 2. It is possible to reduce still further the 65 inertia of the carrier by constructing it of

a light material like aluminum, but I have found the construction indicated to be sufficiently light not to require the use of such a material.

While I prefer to give the carrier 6 movement through a frictional actuating means, it is not essential that the slip-drive actuation be wholly frictional. Means having a light frictional engagement of great effectiveness for the purpose is shown in my 70 drawings.

Referring first to Figs. 1, 2 and 3,—mounted upon the platen-arbor 13 adjacent to one end of the platen 10 are the frictional driving disks 11^a and 11^b. The disk 11^a is next to the platen-end. Between the rims of the two disks 11^a and 11^b is entered an inwardly-projecting-portion or lip 84 of the index-carrier 6. The outer lateral face of the said inwardly-projecting lip constitutes a shoulder, into contact with which the rim-portion of the disk 11^b is pressed by means of a spring 7 acting axially with relation to the arbor 13. There is, therefore, frictional driving engagement between the 75 disk 11^b and the shoulder of the carrier. The pressure of the spring 7 operates to hold the inner surface of lip 84 in close frictional contact with the rim-portion of disk 11^a. Thus the lip 84 is embraced between two 80 frictional contact-surfaces. The spring 7 is of dished form, with a central eye that encircles the platen-arbor, and with three branches which bear by their extremities against the said outer lateral surface of the 85 rim-portion of disk 11^b. The spring 7 is confined between the disk 11^b and a face-disk 11^c, the latter being sleeved upon the platen-arbor, and by means of a clamping screw 83 being secured in place on the 90 platen-arbor. The disk 11^c fits within the opening at the outer side of the index-carrier, and closes such opening. The spring 7 therefore acts axially with respect to the 95 platen-arbor 13. Annulus 6 is supported on the peripheries of the disks 11^b and 11^c, and is held from lateral displacement by the lip 84 entering between disks 11^a and 11^b. The tension of spring 7 is regulated in 100 order to vary the degree of frictional driving action tending to rotate the same simultaneously with the platen, by means of adjusting screws 9, 9, the stems of which pass through holes in disks 11^b and 11^c, and screw into threaded holes that are tapped in the 105 disk 11^a, while the flanged heads thereof engage with the disk 11^b. To regulate the 110 tension of the spring 7, the screws 9, 9, are turned so as to adjust the disks 11^a and 11^b closer together or allow them to separate 115 more or less under the tendency of the spring 7 to expand. The annulus 6, and the disks 11^a, 11^b, 11^c, with its hub, and spring 7, are held together by means of screws 9, 9, as 120 an assembled unit, and are applicable to the 125 130

platen-arbor 18 and removable therefrom as an assembled unit.

The invention is not limited to the particular form of the spring, nor to the precise character of adjusting devices, and in some cases, if desired, adjusting means may be omitted.

The slip-driving means just described serve to cause the index-carrier to turn simultaneously with the platen, except when the index-carrier is held from rotation, in which case the platen turns without turning the index-carrier.

Referring, now, to the feeler devices,—the frame extension 22 on the carriage frame 12 bears the laterally extending pin or axle 20 having a shoulder. Journaled on the said pin against the said shoulder is the short sleeve 21 bearing the fixedly attached stop-lever 15. Against the said sleeve and journaled upon the same pin therewith is the sleeve 21, bearing the fixedly attached eccentrically-disposed weight 66, and the fixedly attached paper-feeler butt 28¹. The said butt bears the pin 23, upon which is pivoted the paper-feeler 28. A stop-pin 24 on the said butt coöperates with a lug 65 on the said feeler to give a one-way knuckle flexion to the parts. A one-way stop-pin 62 on the before-named weight 66 likewise coöperates with the lug 63 on the stop-lever 15 to limit the movement of the stop-lever in one direction with respect to the weight. The paper-table 8, carried in usual manner upon the carriage frame 12, is supplied with a slot or opening 4, into which the before-named paper-feeler 28 has its path. I place the centers 20 and 13 as close together as is convenient, and employ a relatively short stop-lever 15 and a relatively long paper-feeler, in order that through the advantage in leverage the pressure of the feeler upon the sheet may be rendered lighter than it otherwise would be. The stop-lever 15 is arranged to engage with a projection 14 extending laterally from the operative member or index-carrier 6.

The action of the mechanism is as follows: The paper-feeler under the action of eccentric weight 66 as transmitted by sleeve 21, normally occupies a position retracted from the paper-table and against the platen, as shown in Fig. 1, to permit of free sheet insertion, the side of the platen 10 serving as a stop to limit the weight-actuated movement of the paper-feeler. The stop-lever 15 is maintained normally in the path of the projection 14 under the action of the same weight as transmitted by stop 62 to projection 63. The paper-sheet 45 is entered into the machine along the paper-table 8, and advanced in the usual way through the instrumentality of the platen. As the platen is rotated, the annulus or carrier 6 also rotates under the frictional actuation of the

same by the frictional driving disks 11¹ and 11², and the projection 14 is eventually brought around thereby until it encounters the stop-lever 15 in its path. Further rotation of the platen presses the projection 14 against the said stop-lever, and through it presses the paper-feeler 28 toward the paper-path. If the sheet were not present, the paper-feeler would continue to be moved by the stop-lever until it had entered the slot 4 sufficiently far to permit the projection 14 to pass the said stop-lever, whereupon both paper-feeler and stop-lever would be returned to normal position by the weight 66. In that case the carrier 6 would continue revolving with the platen without detention. When the sheet is present, the paper-feeler cannot enter the slot 4, but is detained by the sheet, and in turn maintains the stop-lever 15 in the path of the projection 14 so as to act as a stop thereon, and through the projection as a stop upon the carrier or indicator 6. The parts are maintained in this relation and position during the further progress of the sheet until the end of the sheet passes out from under the feeler 28. The instant the slot 4 is cleared by the sheet, the said feeler, no longer restrained from entering the slot, passes into the slot, and the revoluble part 6, no longer detained by the stop 15, takes up its movement with the platen, moving thereafter coördinately with the platen advanced sheet. As the said part 6 always begins its movement from the same angular position, it will always stop in a given angular position after a given angular movement from starting position, and as moreover it always begins its said movement when the end of the sheet is a constant distance from the printing point, since the point where the feeler-end meets the sheet is necessarily fixedly distant from the printing point, and as the sheet is advanced coördinately with the said part during the said movement of the member, the end of the sheet will always be a constant distance from the printing point at the end of the said given angular movement of the carrier. I place the stationary index 34, shown as carried on the carriage frame 12, adjacent to the said carrier, and I supply the indicating portion of the said carrier which is presented opposite the said stationary index in the constant starting position of the carrier with an index 89. Fig. 2, that will indicate that position of the carrier; I further supply the said carrier on that portion thereof which is presented opposite the stationary index after an advance of the sheet and carrier coördinately with each other, with an index that will indicate the new position of the sheet; and so on around the carrier for every successive position of the sheet, at will. That is to say, if after the first movement of the re- 130

leased index-carrier the end of the sheet is distant seventeen single lines from the printing point, I supply the indicating portion of the carrier then in indicating position with the index 17, and in order to indicate when the end of the sheet is distant sixteen single lines, I supply the carrier with the index 16, and so on down to the end of the sheet. In my drawings I show the indication by single line progresses, the indices here being numerals in descending order. Other indication than by single line indication may be employed, and other units than the line unit. It is of course immaterial whether the stationary and the movable indices come to relative rest exactly opposite one another, or whether the distance be given to the end of the sheet or to a point a fixed distance therefrom, or whether the indices in themselves signify distance-units at all. I prefer to use simple numerals indicating the decreasing distances to the end of the sheet and involving no mental calculation nor memorizing on the part of the operator.

My invention serves to give the operator a signal that the end of the sheet is near. I use for a stationary index a shield-pointer that conceals one portion of the carrier from the operator, and the carrier itself is divided into two differently appearing segments, one of which is visible to the operator during the detained position of the carrier, and the other of which is not visible but lies behind the shield-pointer in that position of the carrier. In my drawings I show the first named of these segments as containing no indices except the circular index 89, and by preference I color this segment black, and the second of these segments which I cause to bear indices I prefer to supply with a ground of white, although these are not the only distinguishing means possible. When the sheet-end releases the carrier, and the white index-bearing segment comes into view, the change from black to white attracts the operator's attention and he knows that the end of the sheet is within a given distance away from his printing point. It is of course not essential that the white index-bearing segment should come into view at the very first feed-movement of the platen after the release of the carrier to move therewith—the black segment may be extended under the shield-pointer to any required extent so that several feed-movements will intervene before the white segment with its indices comes into view, so that this signal may be given when the sheet-end attains any required distance from the printing point. It is not essential that the white segment be supplied with indices, nor that the index-bearing portion of the carrier be distinguished from the other portion.

Fig. 4 represents a modification of my invention, described as follows: Fixedly attached upon the platen arbor 13 is the frictional driver 11^a, supplied with a terrace or shoulder, upon which is placed the friction washer 11^b, and against the said friction washer is placed the instanding portion or web 84' of the index-carrier 6'. A dished sheet spring 7' confined between said portion or web and the sleeve 106, bears 75 against one face of the said instanding portion or web 84, the said spring acting with axially directed pressure so that the carrier is pressed axially against the said friction washer 11^b and held in frictional connection therewith, and therefore in frictional connection with the platen so as to turn with the platen. A face-disk 11^c journaled loosely on the sleeve 106 so as to rotate freely thereon in effect forms part of the 85 said carrier through being fixedly connected with the rim-portion of the carrier. As compared with the mechanism previously described, one difference between the two is that the spring 7, Figs. 1 and 2, rotates 90 with the platen; and another difference is that the spring 7', (Fig. 4), bears immediately upon the instanding portion 84' of the carrier, whereas the spring 7, (Fig. 2) produces its effect upon the instanding portion 84 through an intermediate part; and still another is that the carrier 6 in Fig. 2 is an annulus, or annular in form, whereas the carrier 6' of Fig. 4 is more nearly a drum in form. These differences are mere 100 differences in form. The carrier 6', in practice is supplied with indices and visual signaling means such as have been described in connection with the first three figures. The sheet controlled parts are also the same, 105 except that the stop-lever 15' has a bevel 30 upon it and the projection 14' a coöperating bevel 31 upon it, the engagement of the projection and the stop-lever resulting not only in a stopping action upon the projection but tending at the same time through the bevels to press the carrier 6' axially away from the frictional driver 11^a and to open or ease the friction between the said parts. In other respects the action of the mechanism is the same as that of the mechanism 115 first described.

Provision is made for backward movement of the sheet at any time, in two ways. If the platen is moved backwardly while the 120 feeler is in contact with the sheet, the resulting backward movement of the carrier 6 will cause the projection 14 to move backwardly, relieving the stop 15 of pressure, whereupon the weight 66 will be permitted 125 to retract the feeler from contact with the sheet. And if the sheet be advanced to a point just after it has released the feeler, and the mechanism is then moved backwardly, the bottom edge of the sheet will carry the 130

feeler 28 backwardly ahead of it, the axis 23 and the one-way stop 24 permitting the movement, and at the same time the weight 66 will move the feeler-butt 28' toward the platen until the feeler clears the sheet.

5 A mechanism such as I have described satisfies the objects of my invention in what I regard as the most perfect manner, but I consider my invention sufficiently broad to 10 include within its scope various known types of indicating or signaling devices, either visual or audible, which may prove suitable and convenient for use in practical embodiments of the main principles of the invention. I regard the indicating segments shown and described as constituting an adequate signaling means. In addition they inform the operator of the exact position of the bottom of the sheet.

15 20 It is to be noted that the index-bearing part in some embodiments of certain of the features of the invention may vary more or less in character and construction in practice, and the means and manner of actuating the same may vary without departure from the principles of the invention. It is to be noted, also, that although I show the paper-feeler 28 as intersecting the path of the paper-sheet at the paper-table 8, I do not limit 25 myself to this construction.

The devices shown in the drawings and described herein are part of a series of closely related inventions or improvements which are presented in a number of co-pending applications for Letters Patent filed by me. The said devices have a number of general objects in common with those forming the subject-matter of different applications in the said series, and to a certain extent embody and utilize various principles and features which are common to devices shown and described in one or another of the said applications. Some of the said common principles and features are 40 claimed broadly in my divisional application aforesaid, and in my application filed April 20, 1908, aforesaid, while others are made more particularly the subject of claim in my applications filed Dec. 15, 1909, Serial No. 533,309, and Mar. 30, 1912, Serial No. 687,463. The branch of the general invention that is covered hereby is distinguished by the characteristic features which are specified in the following claims.

55 Having thus clearly explained the nature and objects of my invention and the manner of applying the same, I claim as new and desire to secure by Letters Patent—

1. In a typewriting machine, in combination, a platen, a series of indices, frictional means having a constant spring-pressed engagement acting to give the said indices movement correlated with that of the platen, and sheet-controlled means for detaining and releasing the said indices.

2. In a typewriting machine, in combination, a platen, an operative member, frictional means having a constant spring-pressed engagement acting to give the said member movement correlated with that of the platen, a sheet-controlled stop for detaining and releasing the said member, and indicating means called into operation through said member.

3. In a typewriting machine, in combination, a platen, an indicator, frictional means having a constant spring-pressed engagement acting to give the said indicator movement correlated with that of the platen, and a paper-feeler controlling the movement of the said indicator so that it will be suitably held in constant starting position and suitably released to move with the sheet when the sheet-end attains a constant distance from the printing point.

4. In a typewriting machine, in combination, a platen, an index-carrier and a connected projection, frictional means having a constant spring-pressed engagement acting to give the said carrier movement correlated with that of the platen, and sheet-controlled means for detaining and releasing the said carrier through the said projection.

5. In a typewriting machine, in combination, a platen, an index, frictional means having a constant spring-pressed engagement acting to give the said index movement correlated with that of the platen, and a sheet-controlled stop for detaining and releasing the said index so that it takes up movement with the sheet at a constant point in the progress of the end of the sheet.

6. In a typewriting machine, in combination, a platen, an operative member, indicating means called into operation through said member, frictional means including an axially acting dished pressure spring for giving the said member movement with the platen, and sheet-controlled means for detaining and releasing the said member.

7. In a typewriting machine, in combination, a platen, an operative member, indicating means called into operation through said member, frictional actuating means for the said member, including a symmetrically disposed axially pressing spring, and sheet-controlled means for detaining and releasing the said member.

8. In a typewriting machine, in combination, a platen, an operative member, indicating means called into operation through said member, frictional means for giving the said member actuation with the platen, including a driving member and spring-pressure means disposed about the axis thereof, and a paper-feeler connected to control the movement of the said operative member.

9. In a typewriting machine, in combination, a platen, an operative member, indicating means called into operation through said

- member, frictional connecting means between the said member and the platen, including a driving member and a spring disposed about the axis thereof and acting axially, 5 and a sheet-controlled stop for controlling the movement of the said operative member.
10. In a typewriting machine, in combination, a platen, an annulus having an annular shoulder in connection therewith, an axially pressing spring coöperating with the said shoulder to give the said annulus frictional engagement moving it with the platen, and sheet-controlled means for detaining and releasing the said annulus.
15. 11. In a typewriting machine, in combination, a platen, an annulus and a connected projection, frictional means including a spring for giving the said annulus movement with the platen, and sheet-controlled 20 means coöperating with the said projection to detain and release the said annulus.
12. In a typewriting machine, in combination, a platen, an annulus and a connected projection, frictional means including 25 an axially-pressing spring for giving the said annulus movement with the platen, and a paper-feeler connected to control the
- movement of the said annulus through the said projection.
13. In a typewriting machine, in combination, a platen, an annulus frictionally connected through spring-pressure to move normally with the platen, and sheet controlled means for controlling the movement of the said annulus. 30
14. In a typewriting machine, in combination, a platen, an operative member bearing a fixedly attached projection, indicating means called into operation through said member, frictional connecting means 35 between the said member and the platen, having a pressure-spring with central backing, and sheet-controlled means for detaining the said member in constant starting position and for releasing the member to move with the platen when the sheet-end arrives at a constant distance from the printing point. 40
- 45

In testimony whereof I affix my signature in presence of two witnesses,

WILLIAM J. NEIDIG.
